Attorney

UNITED STATES PATENT OFFICE.

LEWIS A. EASTMAN, OF LACONIA, NEW HAMPSHIRE.

OIL-BURNER.

1,296,935.

Specification of Letters Patent. Patented Mar. 11, 1919.

Application filed September 26, 1918. Serial No. 255,838.

To all whom it may concern:

Be it known that I, LEWIS A. EASTMAN, a citizen of the United States, residing at Laconia, in the county of Belknap and State of New Hampshire, have invented certain new and useful Improvements in Oil-Burners, of which the following is a specification.

This invention relates to hydro-carbon burners, and more particularly to those designed for use in connection with fire boxes of heating and cooking stoves.

The object of the invention is to provide a simply constructed, cheap and efficient burner of this character, which while producing a maximum amount of heat consumes a minimum quantity of fuel.

Another object is to provide a burner of this character with means for directing the heat to any desired point.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a side elevation of a burner constructed in accordance with this invention, and

Fig. 2 is a top plan view thereof.

In the embodiment illustrated a base plate 1 is shown, which may be of any suitable or desired configuration, being rectangular as illustrated, and provided on its lower face with an oil chamber 2. This plate is mounted on supporting wheels 3 and has rising from the oil chamber 2 a pipe 4 which may be of any desired height. A U-shaped burner pipe 5 has one leg connected with the upper end of pipe 4 and extending laterally and forwardly therefrom with its other leg arranged below it and in vertical alinement therewith. The lower leg 7 has burner nipples 8, any desired number of which may be employed, two being here shown, and the free end of said leg is closed by any suitable means. The upper leg 9 carries heat deflectors 10 which are adjustable on said leg to provide for the directing of the flames from the nipples 8 in the desired direction. These deflectors 10 are arranged above the nipples 8 through which the flame passes and

is directed against the deflectors in the manner above set forth.

An oil supply tank 11 of any desired size is adapted to be suspended on a suitable support in a plane above the burner proper, and is provided with an outlet having a cock 12 which is connected by a coupling 13 with a pipe 14. This pipe 14 may be of any desired length, and is preferably flexible to permit it to be inserted between the grate bars of a furnace or stove. This pipe 14 is connected by a coupling 15 with an upright pipe 16 equipped with a valve 17 for controlling the supply of fuel through pipe 16. This pipe 16 is united with the chamber 2 by a suitable coupling 18 and is designed to supply oil to the burner proper.

As shown, the tank 11 has brackets 19 carried by its lower end and a hanger 20 for engagement with a nail to assist in supporting the tank in upright position.

In the use of this burner, the base 1 is placed within a stove fire box with the wheels 3 resting on the bottom thereof, and the pipes 14 and 16 extending between the grate bars, the tank 11 being suspended from any suitable and convenient support. When in this position, the tank 11 having been first filled with kerosene, the cock 12 is opened to permit the passage of fuel through pipes 14 and 16 to the chamber 2. The fuel in chamber 2 rises through pipe 14 and passes into the legs 7 and 9 of the burner proper. The supply of fuel to the chamber 2 may be controlled by the valve 7.

To start the fire or light the burner, a little oil is permitted to flow out through both nipples 8 on to a piece of asbestos, not shown, which is placed on the base 1. The oil-soaked asbestos is then ignited which will cause the flame to rise and encompass leg 7 of the burner thereby vaporizing the fuel container therein which will ignite at the exit of nipples 8 and shoot upward against the spreaders 10, being distributed thereby and flared outwardly forming a large volume of heat producing flame.

A stopper 6 is designed to be inserted in one or the other of the burner nipples 8 after sufficient heat has been generated, so that a uniform heat may be maintained indefinitely. As shown, the stopper 6 is in the form of an S-shaped piece of wire having a weight 6' on one end and its other end adapted to fit closely within one of the nipples and operate as a closure therefor.

This burner, with both flames in operation will heat an oven in about twenty minutes, more or less, and if it is desired to direct all of the heat into the oven, the spreaders 10 5 are tilted toward the oven causing the flame to be directed thereagainst. Likewise, the flame may be directed in any other direction by the adjustment of these spreaders.

It is to be understood that the flame will 10 be controlled by regulation of valve 17.

While this burner is described for use in connection with a cooking stove, it is obvious that it may be used equally well in the fire box of a heating stove or furnace.

15 From the foregoing description, taken in connection with the accompanying drawings, the advantages of the construction and of the method of operation will be readily apparent to those skilled in the art to which 20 the invention appertains and while I have described the principle of operation of the invention together with the device which I now consider to be the best embodiment

thereof, I desire to have it understood that the device shown is merely illustrative and 25 that such changes may be made as are within the scope of the claimed invention.

Having thus fully described my invention, what I claim as new and desire to secure by Letters Patent, is:—

30 A burner of the class described comprising a wheel-supported base plate having a chamber on its lower face, fuel supply means connected with said chamber, a valve for controlling said supply, parallel pipes arranged above said plate in vertical alinement with each other, means for connecting said pipes with said chamber, nipples carried by the lower pipe, and a stopper for closing one of said nipples.

40 In testimony whereof I affix my signature in presence of two witnesses.

LEWIS A. EASTMAN.
